UNITED STATES PATENT OFFICE.

ERNEST R. SIBERT, OF COLORADO SPRINGS, COLORADO.

CHUCK.

No. 906,315.

Specification of Letters Patent.

Patented Dec. 8, 1908.

Application filed August 8, 1908. Serial No. 447,603.

To all whom it may concern:

Be it known that I, ERNEST R. SIBERT, a citizen of the United States, residing at Colorado Springs, in the county of El Paso and State of Colorado, have invented new and useful Improvements in Chucks, of which the following is a specification.

My invention pertains to chucks for use on polishing or buffing lathes and turning lathes; and it contemplates the provision of a chuck constructed with a view of saving time when it is necessary to stop a tool carrier in order to examine the work that is being turned or to remove a buff from the tool carrier and replace it with a buff of different character, the starting or stopping of the tool carrier in order to attain the ends stated being accomplished without the necessity of stopping the lathe. This will be appreciated when it is remembered that in those cases where electric power is used, the starting of the lathe involves the loss of considerable power, and that, therefore, my improvements are materially advantageous because a saving of both time and power expense is effected by the use thereof.

With the foregoing in mind, the nature of my invention, and its novelty, utility and practical advantages will be fully understood from the following description and claims when the same are read in connection with the drawings, accompanying and forming part of this specification, in which:

Figure 1 is a general view of the chuck constituting the best practical embodiment of my invention of which I am cognizant. Fig. 2 is a longitudinal, diametrical section of the chuck; the same being shown with the buff removed from the tool-carrier which is illustrated as adapted for the connection of a buff. Figs. 3 and 4 are transverse sections of the chuck taken in the planes indicated by the lines 3-3 and 4-4, respectively, of Fig. 2.

Similar letters designate corresponding parts in all of the views of the drawings, referring to which:

A is an arbor. B a tool-carrier, shown specifically as a buff-carrier, and C, a "shift" sleeve, comprised in the construction illustrated. The arbor A is exteriorly threaded at its rear end for connection to the lathe portion from which it is to derive motion, and is provided with the following features, to wit: an oil cup b, an oil duct c extending from the cup b to the side of the arbor at an

intermediate point in the length thereof, and designed to lead oil to the hard-felt washer, presently described, a shoulder or flange d arranged on the outside of the arbor, and a 60 slightly tapered forward end e. The said tapered portion e of the arbor is designed to coöperate with the tapered portion f of the socket g in the buff carrier B, which buff-carrier is provided, in addition to the socket g, 65 with a forwardly tapered and exteriorly threaded portion h and with a rear exteriorly threaded portion i. In its forward end the arbor A is preferably provided with a kerf for the engagement of a screw-driver 70 employed in disengaging arbor from the lathe spindle. The said exteriorly threaded portion i of the buff carrier B is for the engagement of a "shift" nut D and a lock nut E; the "shift" nut D being provided with a 75 bank pin j, and the lock nut E having a similar pin k, and said pins having for their purpose to prevent the two nuts from becoming locked. It will also be observed by reference to Figs. 2 and 3 that the lock nut E is 80 provided with a screw l by which it is fixed on the portion i of the buff-carrier, and that carried in the "shift" sleeve C are three (more or less) screws m by which it is fixed to the "shift" nut D. It will be noticed at this 85 point that the exterior thread on the portion i of the buff-carrier B is designed to serve as a "shift" screw, and that the portion e of the arbor A is designed to serve as a friction taper. Said portion e of the arbor and the 90 rear end of the "shift" sleeve are preferably case-hardened. It will be noted here that in addition to the screws m, the "shift" sleeve C is provided in rear of the shoulder or flange d with an inwardly directed flange r, and that 95 a hard-fiber washer r² is interposed between said flanges, this in order to render the running of the chuck practically noiseless, and prevent cutting of the bearing.

As will be observed by reference to Fig. 2 100 the eduction orifice of the oil duct c is surrounded by a washer F, of hard-felt or other suitable hard, absorbent material, which is inclosed in the "shift" sleeve C, and it will also be observed that an oil vacuum is afforded between the forward end of the arbor and the opposed end wall of the socket g in the buff-carrier.

The felt washer F serves to supply the 110 inclosed parts with oil so as to render the chuck self-lubricating for an indefinite period, and also serves for the frictional transmission of

motion to the "shift" sleeve C which, in turn, carries the "shift" nut D towards the left and draws the tool-carrier B in the same direction to engage said carrier with the 5 arbor at the friction portion e thereof. The mentioned oil vacuum has for its office to form a cushion at the forward end of the arbor A to prevent the same becoming jammed in the socket g of the tool-carrier. The 10 "shift" nut D serves to carry the tool-carrier B back and forth from locking point to unlocking. The screw l holding the lock nut E on the tool-carrier B may be loosened when it is desired to adjust the nut to gage 15 the cushion effect in the before mentioned oil vacuum. By adjustment of the lock nut E, the locking and unlocking at E and F are equalized.

In the practical use of my novel chuck, it is 20 simply necessary when the tool-carrier B is to be stopped for the operator to take hold of and stop the "shift" sleeve C.

It will be obvious from the foregoing that my improvements may be embodied in a 25 chuck having a tool-carrier at the right-hand end thereof, as shown, or in a chuck having a tool-carrier at the left-hand end thereof, the only difference between the two chucks residing in the disposition of the threads on 30 certain parts thereof.

Experience has demonstrated that when my novel chuck is used in connection with a polishing buff it saves approximately one-half of the time necessary to a polishing operation and approximately one-third of the 35 electric energy employed to drive the lathe spindle.

Having described my invention, what I 40 claim and desire to secure by Letters-Pat- ent, is:

1. A chuck for the purpose described, comprising an arbor, a tool-carrier, and means for rotating the tool-carrier incidental to rotation of the arbor and adapted when 45 stopped to effect stoppage of the tool-carrier.

2. In a chuck, the combination of an arbor,

a tool-carrier, a "shift" sleeve, means intermediate the arbor and the "shift" sleeve for rotating the latter by the former, and means intermediate the "shift" sleeve and 50 the tool-carrier for normally rotating the tool-carrier incidental to rotation of the arbor and adapted when the "shift" sleeve is stopped to effect stoppage of the tool-carrier notwithstanding the continued rotation of the arbor. 55

3. The combination in a chuck, of an arbor having an exterior shoulder or flange and a friction taper, a tool-carrier socketed to receive the arbor and the friction taper thereof 60 and having a rear, exteriorly threaded portion, a "shift" nut on said threaded portion, a "shift" sleeve connected with the said "shift" nut and having a flange disposed in rear of the shoulder or flange of the arbor, 65 and a friction washer interposed between the arbor and the "shift" sleeve.

4. The combination in a chuck, of an arbor having an exterior shoulder or flange and a friction taper and also having an oil duct the 70 ejection orifice of which is disposed at its side, a friction washer, of absorbent material, surrounding the arbor and arranged to receive oil from the said duct, a tool-carrier socketed to receive the arbor and the friction 75 taper thereof and having a rear exteriorly threaded portion, a "shift" nut arranged on said threaded portion and provided with a bank pin, a lock nut detachably fixed on said threaded portion and also having a bank pin, 80 and a "shift" sleeve surrounding the rear portion of the tool-carrier, the nuts and the friction washer and connected with the "shift" nut and having a flange disposed in rear of the shoulder or flange of the arbor. 85

In testimony whereof I have hereunto set my hand in presence of two subscribing witnesses.

ERNEST R. SIBERT.
